RIBBON-SPOOL.

1,146,551.

Specification of Letters Patent. Patented July 13, 1915.

Application filed December 18, 1914. Serial No. 877,957.

To all whom it may concern:

Be it known that we, MICHAEL J. CLABBY and WILLIAM H. FALLON, citizens of the United States, and residents of Bridgeport, in the county of Fairfield and State of Connecticut, have invented certain new and useful Improvements in Ribbon-Spools, of which the following is a specification.

This invention relates to improvements in spools, especially ribbon spools of typewriting machines, and in the art or method of making the ribbon - cores, or hubs of the spools, the main objects of the invention being to facilitate the construction of ribbon spools, to reduce their weight, and consequently the expense of handling and transporting them, the effort required to actuate them in machines, and the wear to which their operation subjects other parts of the ribbon mechanism, and to render them cheaper than ribbon-spools now commonly used.

The invention consists in the features of construction of the spool and its hub and in the method of making the same, all as hereinafter described and set forth in the appended claims.

On the accompanying sheet of drawings, on which like reference numerals designate like parts of different views, Figure 1 is an end view of a ribbon-spool made by said method and embodying said features of construction, its hub being tubular and including a spindle-tube; Fig. 2, an edge view thereof; Fig. 3, a face view of one of the heads of the spool; Fig. 4, a cross-section of the spool on the plane indicated by the line α , α , Fig. 1; Fig. 5, an end view of the hub; Fig. 6, a longitudinal section thereof on the plane y , y , Fig. 5; Fig. 7, a side view of the hub; Fig. 8, a plan of a blank from which the hub is formed by bending operations to which the blank is subjected; Fig. 9, an edge view of the blank at the end of the first bending operation; Fig. 10, an edge view thereof at the end of the second bending operation, this being also an end view of the completed spindle tube; and Fig. 11, an edge view thereof at the end of the third bending operation, this being also an end view of the completed spindle-tube and of the nearly completed hub.

The blank (Fig. 8) is thin, flat, and oblong, and is preferably soft steel. On the

longitudinal edges of its central portion 1, 55 are the prongs 2, and in this portion are the two oblong perforations 3, near its ends, and the round perforation 4, midway between the ends and between the longitudinal edges of the blank. In the terminal portions 5 of the blank are the perforations 6, which are separated by the narrow strips 7 from the perforation 3, these strips being at the ends of the central portion and at the inner ends of the terminal portions. The 65 form of the blank and the arrangement of its features are such that it is divisible into two equal parts either by a longitudinal section or a cross section, on a plane which contains a diameter of the perforation 4, 70 and, consequently, when it is subjected to the series of bending operations to be described it does not matter at all which face of the blank is upward or which of its ends is its right or left end. Some of the tools 75 used in the bending operation have pilot pins which enter the perforation 4 and so help to locate the blank in the proper position.

The blank is converted into the form illustrated in Figs. 5, 6 and 7 by four bending operations. The spindle-tube 8, having at its ends the prongs 2, is formed from that part of the central portion of the blank which extends from one of the perforations 85 3 to the other, and the outer portion or drum of the hub, composed of the semi-cylindrical parts 9, is formed from the terminal portions 5 of the blank. The drum and spindle-tube are united by the strips 7, and by the 90 stock 10 at the ends of these strips and at the ends of the perforations 3. The perforations 6 become circumferential, lateral openings in the hub, which are separated by the strips 7, and these strips become cross-bars, or a double cross-bar, to be engaged 95 by a hook or similar device attached to a ribbon. The spindle-tube and the bar or bars 7 may be regarded as parts of internal extensions formed on the semi-cylindrical 100 parts or drum of the hub.

By the first bending operation the blank is bent near its ends and midway between them, so that the drum is partly formed from its terminal portions 5, and the spindle-tube from its central portion 1, as appears by Fig. 9. The second bending operation completes the spindle-tube 8 (Fig. 10).

In the third bending operation (Fig. 11) short bends 11 are made at the intersections of the central and terminal portions, so that at the end of this operation the spindle-tube 5 is nearly surrounded by the curved terminal portions, the curvature of which is somewhat greater than that of the semi-cylindrical parts of the completed hub. The fourth operation further bends the curved terminal portions, so that they are converted into the semi-cylinders 9, and forces them together around the spindle-tube, completing the formation of the united drum and spindle-tube shown in Figs. 5, 6 and 7.

15 Each of the heads 12 of the spool, which are preferably thin sheet-steel, has in it the central perforation 13, with the recesses 14 at its edge, and this is surrounded by the hollow bead 15 formed on the head, so that 20 within the bead, and at the inner side of the head, is an annular space in which either end of the drum will snugly fit. The prongs 2 on the ends of the spindle-tube fit in the recesses 14 and project through the heads 25 and are bent outward against their outer faces, and the ends of the drum are confined in the hollow beads 15. Those portions of each end of the spindle-tube which are between the prongs rest against the inner side 30 of the adjacent head and so co-act with the outwardly bent prongs that the hub and head are firmly secured together, and the inner surface of the spindle-tube is even with those portions of the edge of the 35 perforation 13 which are between the recesses 14. The construction of the hub and the arrangement of the prongs 2, recesses 14 and beads 15 are such that the heads may be alike, and either head and either end of the 40 hub may be fastened together as described.

When the ribbon-spool is in use, the spindle on which it is mounted extends through the perforation 13 in one of the heads of the spool and into the spindle-tube 8, and 45 a pin which forms part of the spool-turning mechanism fits in the hole 16 in the head of the spool. Since the diameter of the perforations 13 is equal to the internal diameter of the spindle-tube, a spindle which 50 fits in either of these perforations will fit in the spindle-tube as an axle fits in the hub of a wagon wheel and will prevent the spool from tipping or wobbling even if the spindle does not extend entirely through it.

55 The finished core or spool hub comprises a central split tubular portion 8 adapted to be fitted upon the spindle of the ribbon mechanism of a typewriting machine, and an outer concentric split tubular portion made integral with the center tubular portion and upon which the inking ribbon is adapted to be wound or coiled. These two concentric tubular portions are connected by radially disposed neck-positions marked 10. The 60 outer tubular portion is formed of half sec-

tions which are bent around the inner tubular section in opposite directions from the outer ends or edges of the neck portions. While in Fig. 5 we have shown a space between the free terminal ends of the outer tubular portion, and also a space between the outer ends of the neck portions or at the points where the roots of the outer half tubular portions join the neck portions, and also a space between the longitudinal split edges of the inner tubular portion, it will be understood that all these spaces are not necessary, and that the respective parts referred to may all be brought into actual contact or in closer relationship than shown. 70 In the finished article it will also be observed that the openings 3, 3 of the blank extend longitudinally of the hub and coincide or register, and that the openings 6, 6 in the blank extend circumferentially of the finished hub in opposite directions from the cross bars 7, 7 which are brought into parallelism and into register by the folding operations above described. The openings 6, 6 75 permit the hook on the ribbon to be passed through either opening and thence through the openings 3 with which they communicate to encircle or partially encircle the cross bars 7, thus forming a ready, convenient and effective means of attaching the ribbon to 80 the spool and of detaching it therefrom.

85 Hubs like that shown may be made in the method described by hand, with the aid of simple metal-bending tools, or by machinery comprising bending and forming dies and not requiring attention by highly skilled workmen, and such machinery has been devised for and is in use in the practice of the method in the manufacture of hubs in large 90 quantities and at low cost.

95 The principle of the invention does not depend on all of the details of the construction and method described, and will not be affected by various modifications which may be made in them.

100 What we claim as new and desire to secure by Letters Patent, is:—

105 1. A spool comprising a tubular drum and a spindle-tube surrounded thereby, the heads of the spool having perforations therein with recesses at their edges, and the spindle-tube having prongs which fit in the recesses and engage the heads, portions of the ends of the spindle-tube being in contact with the inner faces of the heads close to the perforations, and the inner surface of that tube being even with the portions of the edge of each perforation which are between the prongs.

110 2. A spool comprising a tubular drum and a spindle-tube surrounded thereby, both being formed in one piece from sheet metal, the heads of the spool having perforations therein with recesses at their edges, and the spindle-tube having prongs which fit in the 115 120 125 130

recesses and engage the heads, portions of the ends of the spindle-tube being in contact with the inner faces of the heads close to the perforations, and the inner surface of 5 that tube being even with the portions of the edge of each perforation which are between the prongs.

3. A spool comprising a tubular drum and a spindle-tube surrounded thereby, the drum 10 consisting of two semi-cylindrical parts, those parts having internal extensions and the spindle-tube forming a part of those extensions, and the drum having in it lateral openings separated by a cross bar formed by 15 parts of those extensions.

4. A spool comprising a tubular drum and a spindle-tube surrounded thereby, the drum consisting of two semi-cylindrical parts, those parts having internal extensions and 20 the spindle-tube forming a part of those extensions and having at its ends prongs which project through and are fastened in the heads of the spool, and the drum having in it lateral openings separated by a cross 25 bar formed by parts of those extensions.

5. A spool, the hub of which comprises a center split tube, neck portions extending radially outward from the meeting edges of 30 said split tube, and an outer split tube composed of half sections extending in opposite directions around the center tube from the outer ends of said neck portions.

6. A spool comprising a split tubular center, neck portions extending outwardly from 35 the meeting edges of said center, said neck portions having each a slot or opening and a cross bar, and an exterior tubular portion provided with circumferential slots or openings communicating with the aforesaid slots 40 or openings.

7. A spool comprising a split tubular center, neck portions extending outwardly from the meeting edges of said center, said neck portions having each a slot or opening and 45 a cross bar, and a concentric tubular split portion formed of half sections, the roots of which join or spring from the outer edges of the neck portions, said half sections extending therefrom in opposite directions to 50 encircle the center tubular portion and each said half section having a slot or opening communicating with the slots or openings in the neck portions.

8. A spool consisting of two heads or 55 flanges and a sheet metal core or hub, the latter comprising a central split tube pro-

vided at each end with ears or lugs passed through recesses in the heads or flanges and bent over thereupon, and an outer concentric split tube connected to the inner tube by 60 neck portions, said neck portions having slots or openings and a cross bar, and said outer tubular portion having circumferential slots or openings.

9. A spool having a spindle receiving portion, a neck portion having an opening, a ribbon supporting portion having an opening communicating with the neck portion, and a cross bar intermediate said openings.

10. A spool comprising a tubular drum 70 and a spindle-tube made from a thin, flat and oblong blank having a central portion and two terminal portions, the central portion having prongs at each of its longitudinal edges and perforations near its ends, 75 and the terminal portions being alike and having larger perforations, and the blank including narrow strips that separate said perforations of the central portion from those of the terminal portions.

11. The method of making spool hubs from blanks of sheet metal which consists first of forming from the central portion of each blank a tubular portion and neck-like extensions from said tubular portion, and 85 then forming a concentric tubular portion by bending the terminal portions of the blank circularly in opposite directions from said neck portions.

12. The method described of forming a 90 tubular drum and spindle-tube, of a spool, in one piece from sheet metal, the method consisting in first bending an oblong blank near its ends and midway between them and thereby partly forming the drum from the 95 terminal portions and the spindle-tube from the central portion of the blank, then completing the formation of the spindle-tube by further bending the central portion of the blank, then making short bends at the ends 100 of the central portion, and then completing the drum by further bending the terminal portions into semi-cylinders and forcing them together around the spindle-tube.

Signed at Bridgeport, in the county of 105 Fairfield, and State of Connecticut, this 16 day of December A. D. 1914.
